(57) **CLAIM**

The ornamental design for a display screen or a portion thereof with a graphical user interface for tracking progress of a shipment using an autonomous vehicle, as shown and described.

DESCRIPTION

FIG. 1 is a front view of a display screen or a portion thereof with a graphical user interface for tracking progress of a shipment using an autonomous vehicle, showing a first embodiment of the new design; and, FIG. 2 is a second embodiment thereof.

The outer perimeter shows a display screen or a portion thereof. Portions shown in broken line form no part of the claimed design. All other broken lines inside the display screen show portions of the graphical user interface, and form no part of the claimed design.
